No. 697,018.

Patented Apr. 8, 1902.

A. E. RHOADES.
ROVING BREAKER FOR SPINNING FRAMES.

(No Model.)

UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

ROVING-BREAKER FOR SPINNING-FRAMES.

SPECIFICATION forming part of Letters Patent No. 697,018, dated April 8, 1902.

Application filed July 22, 1901. Serial No. 69,245. (No model.)

To all whom it may concern:

Be it known that I, ALONZO E. RHOADES, a citizen of the United States, and a resident of Hopedale, county of Worcester, State of Massachusetts, have invented an Improvement in Roving-Breakers for Spinning-Frames, of which the following description, in connection with the accompanying drawings, is a specification, like characters on the drawings representing like parts.

This invention has for its object the production of novel means for breaking or clamping the roving in a spinning-frame to stop the delivery and the roving upon breakage of a thread between the front rolls and the spindle. Numerous devices have been constructed heretofore to accomplish the same general result; but so far as I am aware the clamping or breaking of the roving has been effected directly by or through breakage of the thread in front of the rolls.

In my present invention the stoppage of the roving delivery is effected by or through the accumulation thereof on the roll provided for that purpose below the front drawing-roll, the apparatus being very simple, efficient, and quickly responsive, the accumulation of roving occurring upon breakage of the thread.

Figure 1 is a part-sectional view from front to back of a portion of a spinning-frame with one embodiment of my invention applied thereto and shown in normal operative position. Fig. 2 is a front elevation of the novel means for effecting the stoppage of the roving delivery. Fig. 3 is a rear elevation of the roving breaker or clamp proper mounted on the traverse or roving bar; and Fig. 4 is a vertical section thereof on the line xx , Fig. 3.

Referring to Fig. 1, the stand D, drawing-rolls d, top rolls d', the traverse or roving bar d^x, guide-board a a', having the pig-tails a², one of which is shown, may be and are of usual and well-known construction, and herein I replace the usual trumpets on the traverse-bar by guides, which form a part of the stopping mechanism.

Beneath the front drawing-roll and in contact therewith I have shown a clearer-roll B, which serves to clear the roving from the

front drawing-roll should the thread break between the drawing-rolls and the spindle and operating in well-known manner, the said clearer-roll preventing the roving from winding onto the front drawing-roll and being herein shown as yieldingly supported in weighted arms b^x, fulcrumed at b on the stand D.

The traverse or roving bar d^x has mounted upon it the roving-breaker proper, it being understood that each roving will be provided with one of the breakers, and herein I have shown the breaker as composed of two members relatively movable, one of the members, as c, being shown as trough-like secured to the back of the traverse-bar by screws s, passed through a cover-plate c^x, having an aperture or eye c' therein for the roving to pass through. The other member is shown as an elongated plate c², adapted to slide longitudinally in the trough-like member c and also provided with an aperture or eye c³, (see Fig. 4,) which normally registers with the aperture c' and with an aperture c⁴ in the bottom of the member c opposite the aperture c'.

The member c² is shown as having an elongated slot c⁵, through which a pin 5 is passed, said pin extending through the cover-plate c^x into the bottom of the trough-like member c and limiting the longitudinal movement of the member c². The latter member extends below the traverse-bar, as clearly shown in Figs. 1 and 4, and at its lower end it is connected with an arm f, fulcrumed on a stud f' to swing laterally to accommodate the back-and-forth movement of the traverse-bar, the stud f' being rigidly mounted in a tipping lever L, fulcrumed on a fixed stud 6 on a stand L^x, rigidly secured to the spinning-frame adjacent the roll-stand D.

The tipping lever is provided with forwardly-extended arms L', notched at 7, which form bearings for a roll L², located beneath the clearer-roll B and normally held in contact therewith by the weight of the swinging arm f.

The fulcrums 6 and f' are shown in Fig. 1 as substantially at right angles to each other, so that while any tipping movement of the

lever L will impart an up-and-down movement to the arm f the latter can swing laterally with the movement of the traverse-bar.

5 A screw-stud 10 is passed loosely through a hole c⁶ in the lower end of the member c² and is screwed into the free end of the arm f to pivotally connect the said arm with the breaker member c².

10 So long as the members of the roving-breaker are in normal position, as shown in the drawings, the apertures or eyes c' c³ c⁴ will register or be in alinement with each other and at such time will constitute a roving-guide, through which the roving is led to the drawing-rolls.

15 Should the thread break between the drawing-rolls and the spindle, the roving will wrap around the clearer-roll B in well-known manner, and as the roving thus accumulates it 20 will act upon the roll L², depressing the latter to tip the lever L on its fulcrum and elevate the rear free end of the arm f. Thereby the breaker member c² will be lifted, and the aperture c³ will be moved out of register 25 with the apertures c' c⁴, and the roving will be clamped and parted between the breaker and the back rolls in well-known manner, and delivery of the roving is consequently stopped, the end of the roving being held by 30 the breaker. When the accumulated roving is removed from the clearer-roll, the tipping lever and its connected arm f will return to normal position, and the member c² of the roving-breaker will resume its normal position, and the roving end will be released.

35 By mounting the roving-breakers at the back of the traverse-bar the distance between them and the back rolls is sufficient to render easy the breakage of a roving when 40 clamped by its coöperating breaker, as described.

45 My invention is not restricted to the precise construction and arrangement herein shown, as I have illustrated one practical embodiment thereof without attempting to show various changes or modifications which might be made by those skilled in the art without departing from the spirit and scope of my invention.

50 Having fully described my invention, what I claim as new, and desire to secure by Letters Patent, is—

55 1. In a spinning-frame, drawing-rolls, a clearer-roll, to take up roving from the drawing-rolls upon breakage of the thread, and means actuated by or through accumulation of roving upon the clearer-roll to clamp and stop delivery of the roving.

60 2. In a spinning-frame, drawing-rolls, means to clear the front roll of roving upon

breakage of the thread, and means to clamp and stop delivery of the roving, said means being controlled and actuated by or through accumulation of roving cleared from the front roll.

65

3. In a spinning-frame, drawing-rolls, means to stop delivery of the roving, said means comprising two apertured and relatively movable members, the apertures normally registering and forming a roving-guide, and means, actuated by or through accumulation of roving upon breakage of the thread, to effect relative movement of said apertured members and part the roving.

4. In a spinning-frame, drawing-rolls, a clearer-roll coöperating with the front roll, a traverse-bar, means mounted thereon to clamp and stop delivery of the roving to said drawing-rolls, said means normally forming a roving-guide, and actuating devices for the said means, operated by or through accumulation of roving upon the clearer-roll upon breakage of the thread.

5. In a spinning-frame, drawing-rolls, a clearer-roll coöperating with the front roll, a traverse-bar, fixed and movable coöperating members mounted thereon and apertured to normally form a roving-guide, movement of one of said members relatively to the other acting to clamp and stop delivery of the roving, and means, including a rocking actuator moved by accumulation of roving upon the clearer-roll, pivotally connected with and to operate said movable member upon breakage of the thread.

6. In a spinning-frame, drawing-rolls, a clearer-roll coöperating therewith, a traverse-bar, a roving-breaker mounted thereon and comprising fixed, and coöperating movable, plates, each having an aperture, the apertures normally registering and forming a roving-guide, and connections between the clearer-roll and the movable plate, said connections including a lever having a fixed fulcrum and adapted to be tipped by accumulation of roving on the clearer-roll, due to breakage of the thread, and a laterally-swinging arm fulcrumed on the lever and connected with the movable plate, to operate it upon tipping of the lever, to thereby move the apertures in the coöperating plates out of register, to clamp and effect breakage of the roving.

95 In testimony whereof I have signed my name to this specification in the presence of two subscribing witnesses.

ALONZO E. RHOADES.
